UNITED STATES PATENT OFFICE.

SAMUEL A. STRANAHAN, OF FLINT, MICHIGAN, ASSIGNOR TO GENERAL MOTORS CORPORATION, OF DETROIT, MICHIGAN, A CORPORATION OF DELAWARE.

GASOLENE-TANK-FILLER CAP.

1,339,485.

Specification of Letters Patent. Patented May 11, 1920.

Application filed September 18, 1919. Serial No. 324,341.

To all whom it may concern:

Be it known that I, SAMUEL ANTHONY STRANAHAN, a citizen of the United States, and resident of Flint, Genesee county, State 5 of Michigan, have invented certain new and useful Improvements in Gasolene-Tank-Filler Caps, of which the following is a specification.

My invention relates to closures or caps 10 for the filling openings of the gasolene tanks of automobiles and similar motor vehicles, although the same may be used as a closure for any tank or receptacle within which a liquid is contained, and which is likely to 15 splash up into the opening closed by the cap and leak through the joint between the cap and the opening.

The object of my invention is to provide 20 a filling opening closing cap of the type above referred to and especially adapted for use with the gasolene tanks of automobiles, and which cap is provided with an improved form of baffle construction for preventing the gasolene within the tank from 25 leaking past the joint between the cap and the filling passage through which the tank is filled, due to the splashing of the liquid within the tank; the construction and arrangement of the baffle device being such 30 that such gasolene or other liquid as may splash up into the cap will be promptly returned to the interior of the tank, and not permitted to seep through the threaded or other form of joint between the filling opening and the cap for closing the same.

A further object of my invention is to 35 provide an improved closing cap for the gasolene supply opening of a gasolene tank; said cap having baffles for preventing the escape of liquid from the interior of the tank, and having also a vent leading to the external atmosphere and through which air may flow into the tank and out therefrom due to the movement of liquid within the 45 tank.

A further object of my invention is to 50 provide a gasolene tank filling opening cap which will be simple in construction, and which may be manufactured at a minimum 55 of expense and by improved manufacturing processes; and which at the same time will be effective for the purpose of preventing leakage of gasolene past the joint between the cap and filling opening and to the exterior of the tank.

With the above and other objects of invention in view, my invention consists of the improved gasolene tank filling opening cap illustrated in the accompanying drawing and hereinafter described and claimed, 60 and in such variations and modifications thereof, within the scope of the concluding claims, as will be obvious to those skilled in the art to which my invention relates.

Referring to the drawing wherein the preferred embodiment of my invention is illustrated:

Figure 1 is a view showing my improved gasolene tank cap in plan and broken away in part to show features of internal construction;

Fig. 2 is a view showing the same in section upon a vertical central plane, and;

Fig. 3 is a view showing a section, similar to Fig. 2, of a modified form of my invention.

In the drawing, the reference numeral 4 designates the main body portion of my improved gasolene tank cap, the same being interiorly threaded at 5 to engage the 80 exteriorly threaded extremity of a filling neck or passage through which gasolene may be supplied to the interior of the tank the filling opening of which is closed by my improved cap. Said cap is shown as provided with the usual ears 6 for preventing the slipping of the hand of the operator in screwing the cap in place, or removing it to fill the gasolene tank, although it will be appreciated that features of construction other than the ears may be provided for preventing the slipping of the hands in removing and replacing the cap.

The body portion 4 is provided with an internal annular shoulder 7 located at the 95 inner end of the threaded portion of the cap, and which shoulder provides an annular seat, against which the periphery of a flat combined gasket and baffle 8 rests; said gasket being held in place between the shoulder, 7 and the extremity of the nipple or neck through which gasolene is supplied to the tank when the cap is in place and screwed home, as will be understood. This gasket or baffle is provided with one or more 105 openings; two openings 9 being present in the form of my invention illustrated in Fig. 2, while a single opening 10 is employed in the form thereof illustrated in Fig. 3.

The main body portion 4 of the cap is of 110

hollow construction and is provided with an internal chamber 11, the peripheral walls 12 of which is preferably cylindrical as shown, and which chamber is concentric with 5 and extends upward from the seat provided by the annular shoulder 7; the upper end of said chamber being closed by the top wall 13 of the cap and said top wall being provided with a hole 14 leading from the 10 chamber 11 to the external atmosphere.

Located within the chamber 11 and extending across the same is a baffle plate provided with an opening through which such liquid as may find its way through the openings 15 in the gasket 8 and into the portion of the chamber above the plate, due to the splashing of the liquid within the tank, may flow back into the space below said plate, and thence through the opening 9 or 10 in 20 the gasket 8 and into the interior of the tank; said baffle plate being shown in Figs. 1 and 2 as having a conical upper surface 15 downwardly inclined toward a centrally disposed opening 16, while in the form of 25 my invention illustrated in Fig. 3 the baffle plate 17 is inclined downward and toward an opening 18 located at one side thereof. Both forms of baffle plate illustrated are provided with depending cylindrical side walls 30 19 and 20 which are in contact with the cylindrical surface 12 of the chamber within the body of the cap; and a baffle of either of these forms may be made from a sheet metal disk by subjecting the same to suitable pressing and die shaping operations. 35 The baffle is then pressed into place in the chamber provided by the cylindrical wall 12 for its reception, after which the resiliency of the periphery cylindrical wall there- 40 of operates to hold the same in place within the chamber in which it is located, when such a method of construction of baffle and of assembly thereof with the body of the cap is adopted.

45 The holes 14, 16 and 9 in the form of my invention shown in Fig. 2, and 14, 18 and 10 in the form thereof illustrated in Fig. 3, are shown as off-set one relative to the other, thus providing a construction of cap in 50 which there is no direct and straight communication from the interior of the tank to the external atmosphere.

In either form of my invention herein disclosed it will be appreciated that such 55 gasoline as may enter the cap through the openings in the gasket 8, due to splashing of the liquid within the tank, will tend to return at once through the holes in the gasket and into the tank; the gasket acting to 60 prevent the liquid from running down and into the threaded joint between the cap and the filling opening. At the same time such gasoline as may find its way upward through the opening in the baffle plate and 65 into the upper portion of the chamber 11

in which the uppermost baffle plate is located, will run down the inclined upper surface of said plate and through the opening therein and into the lower portion of said chamber, from which it runs through the 70 openings in the gasket and into the interior of the tank; thus preventing the accumulation of any material quantity of liquid within the cap itself and at the same time providing a vent through which a flow of air 75 may occur into and out from the tank, due to the movement of the liquid contained within the same.

Having thus described and explained my invention, I claim and desire to secure by 80 Letters Patent:

1. A gasoline tank cap of the class described comprising a main body portion inferiorly threaded to engage an exteriorly threaded portion of a filling opening leading into a tank, said body portion having an internal annular seat at the inner end of said threaded portion, a chamber concentric with and above said seat, and a hole leading from said chamber to the external atmosphere; a perforated baffle plate located 85 within the chamber aforesaid and extending across the same and having a cylindrical peripheral wall in contact with the interior of said chamber; and a perforated gasket located within said main body portion and the periphery of which is in engagement with said annular seat. 90

2. A gasoline tank cap of the class described comprising a main body portion inferiorly threaded to engage an exterior threaded portion of a filling opening leading into a tank, said body portion having an internal annular seat at the inner end of said threaded portion, a chamber concentric with and above the level of said seat, and a hole leading from said chamber to the external atmosphere; a baffle plate located within the chamber aforesaid and extending across the same and the surface 105 of which is inclined downward toward an opening provided therein; and a flat perforated gasket located within said main body portion and the periphery of which is in engagement with said annular seat. 110

3. A gasoline tank cap of the class described comprising a main body portion inferiorly threaded to engage an exteriorly threaded portion of a filling opening leading into a tank, said body portion having 115 an internal annular seat at the inner end of said threaded portion, a chamber concentric with and above the level of said seat, and a hole leading from said chamber to the external atmosphere; a baffle plate located 120 within the chamber aforesaid and extending across the same and the surface of which is inclined downward toward an opening provided therein and which baffle plate is provided with a peripheral wall in contact 125 with said annular seat. 130

with the interior of said chamber; and a flat perforated gasket located within said main body portion and the periphery of which is in engagement with said annular seat.

4. A gasolene tank cap of the class described comprising a main body portion threaded to engage a threaded portion of a filling opening leading into a tank, said body portion having an internal annular shoulder, a chamber located above said shoulder, and a hole leading from said chamber to the external atmosphere; a baffle plate located within the chamber aforesaid and extending across the same and having an opening; and a second baffle plate located within said main body portion and the periphery of which is in engagement with said annular shoulder, and which said second baffle plate is provided with an opening.

5. A gasolene tank cap of the class described comprising a main body portion threaded to engage a threaded portion of a filling opening leading into a tank, said body portion having an internal annular shoulder, a chamber located above said shoulder, and a hole leading from said chamber to the external atmosphere; a baffle plate located within the chamber aforesaid and the surface of which is inclined downward toward

an opening provided therein; and a second baffle plate located within said main body portion and the periphery of which is in engagement with said annular shoulder, and which second baffle plate is provided with an opening.

6. A gasolene tank cap of the class described comprising a main body portion threaded to engage a threaded portion of a filling opening leading into a tank, said body portion having an internal annular shoulder, a chamber having a cylindrical side wall located above said shoulder and concentric therewith, and a hole leading from said chamber to the external atmosphere; a baffle plate located within the chamber aforesaid and extending across same, and the surface of which is inclined downward and toward an opening provided therein, and which baffle plate is provided with a cylindrical peripheral wall in contact with an internal cylindrical surface of said chamber; and a second flat baffle plate located within said main body portion and the periphery of which is in engagement with said annular shoulder, and which second baffle plate is provided with an opening.

In testimony whereof I affix my signature.

SAMUEL A. STRANAHAN.
